HENRY R. WARDELL, OF CHICAGO, ILLINOIS, ASSIGNOR, BY MESNE ASSIGNMENTS, TO
H. W. JOHNS-MANVILLE COMPANY, A CORPORATION OF NEW YORK.

ROOFING-CLAMP.

1,321,958.

Specification of Letters Patent. Patented Nov. 18, 1919.

Application filed September 20, 1916, Serial No. 121,214. Renewed May 15, 1919. Serial No. 297,412.

To all whom it may concern:

Be it known that I, HENRY R. WARDELL, a citizen of the United States of America, residing at Chicago, in the county of Cook 5 and State of Illinois, have invented certain new and useful Improvements in Roofing-Clamps, of which the following is a specification.

My invention relates to means for fastening flexible roofing to the roofs and sides of buildings and consists of an improved form 10 of metal clamp which may be nailed to the roof boards or sheathing of the building, firmly clamping the different sheets of roofing material together at their overlapping edges and to the building. In cleats of this type, the object is to produce as binding a grip on the flexible roofing fabric as possible both at and between the nailing points, and 15 to accomplish this result with as thin a metal strip as possible, so as to reduce, as much as possible, the cost of material, the consumption of power in the presses used to stamp out the cleats, and the wear on the dies so 20 employed. Heretofore, various structures have been invented which were designed to produce this binding action on the roofing along the line between the nailing points by 25 stiffening a light metal cleat by means of transverse arching, longitudinal corrugations, etc. While these cleats have been successful to a degree in accomplishing the desired result, they have required complicated forms of dies which have worn out quite 30 rapidly, so that after a period of use of the dies, the cleats stamped out lost their correctness of shape, and also the raised arches and corrugations presented an obstruction to the flow of water over the roof. My 35 present invention overcomes these difficulties and also produces a clamp which has no sharp edges cutting into the roofing. The best form of clamp at present known to me embodying my invention is illustrated in the 40 accompanying sheet of drawings, in which—

Figure 1 is a plan view of the simplest form of clamp;

Fig. 2 is a longitudinal, vertical section, taken on line 2—2 of Fig. 1;

Fig. 3 is a cross-section taken on line 3—3 of Fig. 1;

Fig. 4 is a plan view of a modification, and

Fig. 5 is a side elevation of either form

of clamp, showing it as applied to a seam 55 or joint in the roofing, the under layer of the roofing fabric being shown in cross-section, and the upper one in edge elevation.

Throughout the drawings like reference characters indicate like parts.

1 is a thin strip of metal, preferably mild steel, which is usually stamped out of a sheet of steel with a plurality of nailing domes 2, 2, forced up from the body of the strip, and centrally perforated for passage 65 of nails at 3, 3. These domes are centered substantially along the medial line of the clamp. In the same stamping operation, the flat portions of the strip between the nailing domes are given a curvature or dip 70 downward, as shown at 4, 4, but retain their rectilinear cross-section, as shown in Fig. 3.

In Fig. 5, the clamp is shown as applied to roofing. 14, is a portion of roof board or sheathing of a building. 15 is the under 75 layer of roofing fabric, shown in cross section and 16 is the edge of the upper layer of roofing fabric, which has been overlapped on 15 to form a seam or joint. The clamps are usually placed along the tops of these 80 seams, the nails 5, 5 passing through clamps and both layers of roofing fabric. The downward pressure at the nailing domes, resulting from nailing the clamp down, partly deforms the curved sections 4, 4, but, 85 as the ends of these curved sections are confined against much longitudinal movement by the nails 5, 5 at either end, if said nails are driven straight downward, the curved sections 4, 4, are generally compelled to 90 retain at least a slight portion of their original curvature, even at the end of the nailing operation, as shown in Fig. 5.

In the modification shown in Fig. 4, I employ a metal strip 11, having curved 95 edges, so arranged that the strip is wider at points 12, 12, intermediate of the nailing domes than it is at the junctures with the dome portions. If the curved wave line of each clamp side is made symmetrical with respect to an axis parallel to the major axis of the clamp, such as the dotted line 13—13, a series of the clamps can be stamped out of a sheet without any waste of material, the convex portion of the edge of one clamp 105 fitting into the concave portions of the edge of the next clamp.

In operation, any two nails, as 5, 5, con-

fine the particular downwardly bowed or curved section 4, of the strip between them and drive or thrust it down upon the roofing beneath with a powerful clamping action, 5 when the nails are driven down upon the domes. The material of the strip is thick enough and stiff enough to prevent it buckling or crimping under this thrust, and so it has no opportunity to bend upward away 10 from the roofing, but is forced down onto and partly into the fabric.

The dome centers at which the nailing pressure is applied being all in the substantially medial line of the clamp, there is 15 no chance for the intervening downwardly bowed portions of the strip forming the clamp to twist or turn or spring to one side and thereby avoid wholly or in part the transmission of the nailing pressure. On 20 the contrary they are rigidly held in the line of said nailing pressure and by it are positively driven or clamped down on to the roofing.

In the modification shown in Fig. 4, the 25 greater width of metal at the downwardly curved parts 12, 12, gives greater stiffness and allows still less opportunity for the strip to buckle up when compressed by the nail thrust.

30 If by any chance, one of the nails, while being driven down, bends sidewise under the reaction of the curved portion of the strip, then being placed under compression, so that said curved portion has a chance to 35 straighten out completely instead of having its curvature only partially reduced by the nailing pressure, the spring action of the distorted strip still affords strong pressure upon the roofing beneath. As a result, the 40 roofing fabric is firmly compressed at all points by direct pressure under the nailing domes and by transmitted pressure under the intermediate sections of the clamp. There are, however, no cutting edges forced 45 into the roofing fabric, no continuous ridge or clamp arch is formed to hold back flowing water, and there are no high projec-

tions to be struck by a shovel, when cleaning snow off the roof.

Having thus described my invention, I 50 claim:

1. A clamp for fastening prepared roofing and the like, consisting of a flat strip of metal having a series of properly spaced, 55 perforated nailing domes centered along the substantially medial line of the clamp, the sections between the domes being curved or bowed downward throughout.

2. A clamp for fastening prepared roofing and the like, consisting of a strip of 60 metal having a series of properly spaced, perforated nailing domes, centered along the substantially medial line of the clamp, the sections between the domes being curved or bowed downward throughout, but of rec- 65 tilinear cross section.

3. A clamp for fastening prepared roofing and the like, consisting of a flat strip of metal having a series of properly spaced, 70 perforated nailing domes, centered along the substantially medial line of the clamp, the sections between the domes being curved or bowed downward throughout and having greater width at their mid portions than at 75 their junctures with the dome portions of the clamp.

4. A clamp for fastening prepared roofing and the like, consisting of a flat strip of metal having a series of properly spaced, 80 perforated nailing domes centered along the substantially medial line of the clamp, the sections between the domes being curved or bowed downward throughout, and having greater width at their mid portions than at 85 their junctures with the dome portions of the clamp, the side edges of the clamp forming wave lines each symmetrical with respect to an axis parallel to the major axis of the clamp.

HENRY R. WARDELL.
